UNITED STATES PATENT OFFICE.

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE.

SHEET-FEEDING MECHANISM FOR PRINTING PRESSES.

Application filed December 17, 1927. Serial No. 240,739.

In machines for cutting sheets of varying lengths from a traveling web where the web feeding and cutting mechanisms are adjustable along the sheet feeding mechanism toward 5 and away from the sheet taking device which is traveling at a fixed speed, it has been usual either to drive the sheet feeding mechanism at a fixed speed sufficient to take care of the longest sheet cut from the web; or, as shown 10 in my copending application filed December 13th, 1923, Serial No. 680,437, to provide a common means for varying the speed of the web feeding and cutting mechanisms and the sheet feeding mechanism. Either of these 15 arrangements is satisfactory where the material is firm and heavy and where one cut is made for each revolution of the impression cylinder. However, when lightweight or loosely woven material, such as burlap, is 20 handled, or when the web feeding and cutting mechanisms are speeded up for cutting two sheets from the web for each revolution of the impression cylinder, it is necessary to provide a very wide range of speeds for the 25 sheet feeding mechanism to assure the proper feeding of the sheets thereby to the sheet taking device. To provide for this wide range of speeds and to ensure the utmost accuracy in the speed of the sheet feeding mechanism, 30 I have introduced a manually controlled variable speed mechanism between the main drive for the web feeding and cutting mechanisms and the sheet feeding mechanism, said variable speed mechanism being capable of 35 being adjusted so that the sheet feeding mechanism may be driven at a speed slightly in excess of the speed of the web.

A practical embodiment of my invention is represented in the accompanying drawings, 40 in which

Fig. 1 represents a detail plan view of a rotary printing press with my improvement applied to the sheet feeding mechanism.

Fig. 2 represents a detail side elevation.

Fig. 3 represents a longitudinal vertical section.

Fig. 4 represents a plan view of the manually controlled variable speed mechanism which is located between the main drive and 50 the sheet feeding mechanism.

The main frame of the machine is denoted by 1 and the auxiliary frame or carriage on which the mechanisms for feeding the web and for cutting sheets of varying lengths 55 therefrom is denoted by 2. This auxiliary

frame or carriage is adjustable longitudinally along the main frame to different distances from the sheet taking device, to provide for the cutting and feeding of sheets of varying lengths.

The sheet taking device is herein shown as a set of grippers 3 carried by the impression cylinder 4 which is rotated at a fixed speed from the main drive shaft 5 through 60 the gears 6, 7 and 8.

The web feeding mechanism is herein shown as including the large web feed roll 9 and its pair of coacting rolls 10, 11. The mechanism for cutting the sheets from the web is shown as comprising the coacting rotary and stationary cutters 12 and 13. A guide 14 serves to direct the web from the web feed roll 9 to the cutting mechanism. The shaft 15 of the rotary cutter is driven from the main drive shaft 5 through the gears 16, 17, shaft 18, bevel gears 19, 20, vertical shaft 21, bevel gears 22, 23, horizontal longitudinal shaft 24 and bevel gears 25, 26. The shaft 27 of the web feed roll 9 is driven from the shaft 24 through the gears 28, 29, worm gears 30, 31, cross shaft 32 and gears 33, 34.

The mechanism for feeding the sheets from the cutting mechanism to the sheet taking device, in the present instance the grippers 3 of the impression cylinder 4, is shown as a horizontally arranged endless tape carrier 35 passing around suitable pulleys carried by the cross shafts 36, 37, arranged respectively adjacent to and a distance away from the sheet taking device. This sheet feeding endless 90 tape carrier 35 is driven from the main drive shaft 5 through a manually controlled variable speed mechanism as follows:

An endless drive chain 38 connects a sprocket 39 on the shaft 18 with a sprocket 40 of a variable speed mechanism 41 of well known or approved form; the variable speed mechanism shown herein being of the well known Reeves type in which there are two pairs of coacting cones supporting a V-shaped belt, the two cones of the two pairs being capable of simultaneous movement in opposite directions in order to vary the radii of contact between the belt and cone pairs.

An endless drive chain 42 connects the sprocket 43 of the variable speed mechanism with a sprocket 44 of a cross shaft 45, which shaft has a driving connection with the cross shaft 36 through the gears 46, 47.

To permit the carriage 2 for the web feed-

ing and cutting mechanisms to be adjusted toward and away from the sheet taking device along the endless tape carrier, the sleeve 48 which carries the gears 25 and 28 is slidably mounted on the shaft 24. The variable speed mechanism 41 is provided with a suitable operating handle 49 for manually controlling the mechanism.

From the above description it will be seen that I have provided means whereby the speed of the sheet feeding endless tape carrier may be very accurately adjusted by hand to assure the proper feeding of the sheets thereby to the sheet taking device, it being understood that the speed of this endless tape carrier should be slightly in excess of the surface speed of the web feed roll 9 or, in other words, the speed of travel of the web.

It is evident that various changes may be resorted to in the construction, form and arrangement of the several parts without departing from the spirit and scope of my invention; and hence, I do not intend to be limited to the particular embodiment herein shown and described, but

What I claim is:—

1. Mechanisms for feeding a web and cutting sheets therefrom, a sheet feeding mechanism, a sheet taking device, a carriage for the web feeding and cutting mechanisms adjustable toward and away from the sheet taking device along the sheet feeding mechanism, and a manually controlled variable speed mechanism for driving the sheet feeding mechanism.

2. Mechanisms for feeding a web and cutting sheets therefrom, a sheet taking device, an endless tape carrier for feeding the sheets to the sheet taking device, a carriage for the web feeding and cutting mechanisms adjustable toward and away from the sheet taking device along the endless tape carrier, and a manually controlled variable speed mechanism for driving the sheet feeding endless tape carrier.

3. Mechanisms for feeding a web and cutting sheets therefrom, a main drive therefor, a sheet feeding mechanism, a sheet taking device, a carriage for the web feeding and cutting mechanisms adjustable toward and away from the sheet taking device along the sheet feeding mechanism, and a manually controlled variable speed mechanism located between the main drive and the sheet taking device.

ting mechanisms adjustable toward and away from the sheet taking device along the sheet feeding mechanism, and a manually controlled variable speed mechanism located between the said main drive and the sheet feeding mechanism.

4. Mechanisms for feeding a web and cutting sheets therefrom, a main drive therefor, a sheet taking device, an endless tape carrier for feeding the sheets to the sheet taking device, a carriage for the web feeding and cutting mechanisms adjustable toward and away from the sheet taking device along the endless tape carrier, and a manually controlled variable speed mechanism located between the said main drive and the sheet feeding endless tape carrier.

5. Mechanisms for feeding a web and cutting sheets therefrom including a web feed roll and a drive therefor, a sheet feeding mechanism, a sheet taking device, a carriage for the web feeding and cutting mechanisms adjustable toward and away from the sheet taking device along the sheet feeding mechanism, and a manually controlled variable speed mechanism located between the web feed roll drive and the sheet feeding mechanism whereby the sheet feeding mechanism may be driven at a speed slightly in excess of the surface speed of the said web feed roll.

6. Mechanisms for feeding a web and cutting sheets therefrom including a web feed roll and a drive therefor, a sheet taking device, an endless tape carrier for feeding the sheets to the sheet taking device, a carriage for the web feeding and cutting mechanisms adjustable toward and away from the sheet taking device along the endless tape carrier, and a manually controlled variable speed mechanism located between the web feed roll drive and the sheet feeding endless tape carrier whereby the endless tape carrier may be driven at a speed slightly in excess of the surface speed of the web feed roll.

In testimony, that I claim the foregoing as my invention, I have signed my name this fourteenth day of December, A. D. 1927.

HOWARD M. BARBER
